(57) **CLAIM**

The ornamental design for a seating unit, as shown and described.

DESCRIPTION

FIG. 1 is a front perspective view of a seating unit of Applicant's design;

FIG. 2 is a front elevational view thereof;

FIG. 3 is a rear elevational view thereof;

FIG. 4 is a first side elevational view thereof, the second side elevational view opposite the first side elevational view and being a mirror image thereof;

FIG. 5 is a top plan view thereof; and,

FIG. 6 is a bottom plan view thereof.

The broken lines illustrate portions of the seating unit and form no part of the claimed design.

The appearance of any portion of the seating unit between the break lines forms no part of the claimed design.

1 Claim, 6 Drawing Sheets
